ATTORNEY

UNITED STATES PATENT OFFICE.

SAMUEL J. MILLER AND MICHAEL J. MCKENNA, OF MINNEAPOLIS, MINN.

CARPET-CLEANING REEL.

SPECIFICATION forming part of Letters Patent No. 336,936, dated March 2, 1886.

Application filed December 29, 1884. Serial No. 151,459. (No model.)

To all whom it may concern:

Be it known that we, SAMUEL J. MILLER and MICHAEL J. MCKENNA, citizens of the United States, residing at Minneapolis, in the 5 county of Hennepin and State of Minnesota, have invented certain new and useful Improvements in Carpet-Cleaning Reels, of which the following is a specification, to wit:

This invention relates to an improvement in 10 carpet cleaners; and it consists in certain peculiarities of the construction and operation of the same, substantially as will be hereinafter more fully set forth and claimed.

In order to enable others skilled in the art 15 to which my invention appertains to make and use the same, I will now proceed to describe its construction and operation, referring to the accompanying drawings, in which—

Figure 1 is a longitudinal section, and Fig. 20 2 a transverse section, of a carpet cleaning reel embodying my invention.

A represents a reel, such as ordinarily used in carpet - cleaning machines, composed of heads a and longitudinal slatted slides a' , 25 and has a hinged door, a^2 , for the convenient insertion of the carpet, as usual. Within the reel, at each alternate corner, is secured a "lifter," B, composed of longitudinal bars, b , secured at each end to cross-pieces b' , which

are bolted through the head of the reel, as 30 shown. Three cross-bars, b^2 , are secured to the bars b at suitable intervals, and the ends of these are turned down to form bolts, which pass through the corner of the reel, and are secured by nuts c upon the outer side. This 35 forms a very strong wing or lifter, which catches and lifts the carpet as the reel revolves, and drops it again from the top, completely clearing it of dirt in a short time, and is not liable to injure the carpet in any way. 40

Having thus fully described my invention, what I claim as new, and desire to secure by Letters Patent, is—

The combination, with the angular slatted reel A, of the lifting-wings B at each alternate 45 corner, composed of the bars b , secured at their ends to pieces b' , bolted through the heads of the reel, and having cross-bars b^2 , the ends of which are reduced to form bolts, which pass through the corner, and are secured by 50 nuts c on the outside, substantially as set forth.

In testimony whereof we affix our signatures in presence of two witnesses.

SAMUEL J. MILLER.

MICHAEL J. MCKENNA.
